UNITED STATES PATENT OFFICE.

OTTO S. KING, OF NEW YORK, N. Y.

INDICATOR FOR STORAGE VESSELS.

1,014,486.

Specification of Letters Patent.

Patented Jan. 9, 1912.

Application filed March 28, 1911. Serial No. 617,411.

To all whom it may concern:

Be it known that I, Otto S. KING, a citizen of the United States, and a resident of the city of New York, borough of Manhattan, in the county and State of New York, have invented a new and Improved Indicator for Storage Vessels, of which the following is a full, clear, and exact description.

My invention is an attachment for medicine bottles and storage vessels of all kinds, designed to indicate, both to the eye and to the touch, the nature of the contents.

The object thereof is to prevent people from drinking poison and other deleterious substances, by mistake.

To this end it comprises a signal device which can be attached either to the stopper of the bottle or other storage vessel, or to the neck thereof, by means of which a person handling the same will be informed at a single glance that the contents of the vessel are not intended for internal use.

Reference is to be had to the accompanying drawings forming a part of this specification, in which the same characters of reference indicate the same parts in all the views.

Figure 1 is a view of my improved indicator, showing a form designed for attachment to the stopper of a bottle; Fig. 2 is a longitudinal sectional view through the indicator and the stopper attached thereto; Fig. 3 is a view of my improved indicator in the form which is designed to be fitted around the neck of the bottle or other storage vessel; Fig. 4 is a section on a plane taken through the neck of the bottle and indicator thereon, in the view shown on Fig. 5; and Fig. 5 is a perspective view of a bottle or storage vessel, showing both forms of my improved indicator attached thereto, one being fastened to the cork and the other being fastened to the neck, as shown.

One form of my improved indicator is indicated by the numeral 1. This form comprises a cap which can be made of metal or wood and is designed to be firmly secured in any suitable way to the top of a stopper 2 of a bottle or other storage vessel 3. From the top of this cap rises a shank 4, which supports an integral annular ring 5. This ring receives a button 6, having ears or projections 7 standing out from its opposite faces. This button is flat, but bulges on each side of the ring 5, and it may be made integral with the ring 5 and shank 4 if de-

sired. The button is given a distinctive color, such as red, and the word "Poison", or any other suitable expression, is placed upon the opposite faces of this button 6.

When the stopper 2 having this indicator attached to its outer end is placed on the bottle or storage vessel 3, the eye of any person picking up the same will be attracted by the red color of the disk 6, so that note 65 will infallibly be taken of the word "Poison" thereon. This will give warning that the contents of the vessel 3 are unsafe, which is the purpose of my invention. It will be noted that the outstanding ears 7 will make 70 the red color of the disk or button 6 sufficiently noticeable, even should the indicator be viewed edgewise of the ring portion 5. It will also be observed that this form of 75 my indicator has a distinctive shape, and that a person who has once seen the same will recognize the indicator by the sense of touch, should he happen to take up the bottle in the dark.

The form of indicator shown on Fig. 3 80 consists of a strip of soft metal 10 having a transverse slot 11 in one end. The other end is rounded, as shown at 11', and when the strip is placed in position around the neck of the storage vessel, the end 11' passes 85 through the slot 11 and is bent back, as shown on Fig. 5, to hold the strip in place. Adjacent the end containing the slot 11 are a series of recesses or indentations 12, formed in both edges of the strip. I preferably use 90 three such recesses, and in the bottom of an end recess along one edge, as well as in the opposite end recess on the opposite edge, I form projecting lugs 13. 14 indicates a 95 series of openings through the strip 10; and in these openings I place buttons 15, similar to the button 6, with the exception that these buttons are flat on one side and have projections 16 extending from the other side, as shown, these projections being similar to 100 the ears 7. The projections having the ears 16 may be flat or curved, according to the preference of the maker. I may also make the buttons 15 with the projections 16 thereon integral with the strip 10, if desired; and 105 these buttons and their projections are colored similarly to the button 6, and have the word "Poison", or any other suitable expression, across the faces thereof. The buttons 15 may bulge out from the face of the 110 strip if desired.

It will be seen that two of the buttons 15

are formed in that portion of the strip which has the edge indentations 12, these two buttons having a pair of these indentations 12 lying on opposite edges of the strip 5 10 between them. When the strip is placed around the neck of the bottle 3, it is bent together around the portion lying between the two middle recesses 12, so that the buttons which lie on either side of this portion 10 will stand out, as shown on Fig. 5, and form a projection 17. Each of the lugs 13 will now be bent over to engage one of the recesses 12 along the same edge of the strip 10, to lock the portions containing the two buttons between the lugs 13, on Fig. 3, together, and the end 11' passing through the slot 11 will be bent back against the band 10, and hold the same in place. This band may be used with the indicator 1, as shown on Fig. 20 5, or it may be used alone if desired. The red color of the buttons 15 will warn anyone handling the bottle as to the nature of the contents; and since the band passes entirely around the neck of this bottle or storage vessel, and has the lug 17 formed thereon, the red color of the parts 15 will be apparent from whatever direction the bottle is viewed; and should any person take hold of the bottle, or other vessel, in the dark, 30 the projection 17 will come into contact with his hand and warn him of the danger.

It will be observed that my indicator is not necessarily limited to use on storage vessels or bottles containing poison. I may 35 attach the same to a storage vessel containing inflammable liquids, or any storage vessel, to indicate the nature of the contents, whether the same are poisonous or not. In such a case I merely substitute a suitable 40 word for the word shown in the figures on the drawings. I may also attach the strip 10 around the body of a bottle, or around the handle, or any other projecting part, instead of fastening the same around the neck 45 thereof.

I wish to reserve to myself the right to make such changes in size, shape and arrangement of parts as fairly fall within the scope and spirit of my invention.

Having thus described my invention, I 50 claim as new and desire to secure by Letters Patent:

1. An indicator for storage vessels, comprising a strip of metal having a slot in one 55 end and having recesses in its opposite edges, one of said recesses on each edge having a lug extending from the bottom thereof, and a series of colored markings formed on the face of said strip, each of said markings 60 having an ear of the same color projecting therefrom and characters of warning formed upon its face, the strip being adapted to fit around a projection of the vessel, and hav-

ing its opposite end projecting through the slot to hold the strip in place, part of said strip projecting outward, said part being held in projecting position by means of the lugs formed in the recesses on the sides of said strip being bent over to engage the opposite edges. 65 70

2. An indicator for storage vessels, comprising a strip of metal having a slot in one end and having oppositely-disposed recesses along its lateral edges over a portion of its length, one of said recesses on each edge 75 having a lug extending from the bottom thereof, the said lugs being located at opposite ends of the row of recesses formed in the sides of the strip, the strip being adapted to fit around a projection on the storage vessel, and having its opposite end projecting through the slot to hold the strip in place, part of said strip along its length projecting outward, said part being held in projecting position by means of the lugs 80 85 formed in the recesses on the sides of the strip being bent over to engage a corresponding recess in the opposite edge of the strip.

3. An indicator for a storage vessel, comprising an elongated member adapted to be bent into engagement with the outside surface of a projecting part of said storage vessel, the said member at a point intermediate its ends being bent away from the surface of the said projecting part, and then folded back upon itself and extending inward into reengagement with the surface of the projecting part, said outward and inward extending portions of the said member constituting parallel longitudinal sections forming a projection from the outer curved surface of said elongated member. 90 95 100

4. An indicator for a storage vessel, comprising an elongated member adapted to be bent into engagement with the outside surface of a projecting part of said storage vessel, said member at a point intermediate its ends being bent away from the surface of said projecting part, and then folded back upon itself and extending inward into reengagement with the surface of said projecting part, said outward and inward extending portions of the said member constituting parallel longitudinal sections forming a projection from said elongated member, and means for engaging said sections and holding them in such projecting position. 105 110 115

In testimony whereof I have signed my name to this specification in the presence of two subscribing witnesses.

OTTO S. KING.
